UNITED STATES PATENT OFFICE.

CHARLES W. RENNER, OF ALTOONA, PENNSYLVANIA.

WASTE-GUARD FOR JOURNAL-BOXES.

1,108,004.

Specification of Letters Patent. Patented Aug. 18, 1914.

Application filed February 11, 1914. Serial No. 818,098.

To all whom it may concern:

Be it known that I, CHARLES W. RENNER, a citizen of the United States, residing at Altoona, in the county of Blair and State of Pennsylvania, have invented new and useful Improvements in Waste-Guards for Journal-Boxes, of which the following is a specification.

The invention relates to journal box attachments, and more particularly to the class of waste guards for use in journal boxes.

The primary object of the invention is the provision of a dust guard wherein the same can be mounted on the lid or cover of a journal box and will automatically adjust itself to retain the waste containing the oil within the box to prevent the displacement thereof, the guard being raised with the lid or cover when access is to be had to the interior of the journal box.

Another object of the invention is the provision of a dust guard which is of novel form and is readily and easily mounted in the journal box and also can be removed therefrom.

A further object of the invention is the provision of a waste guard which is simple in construction, reliable and efficient in use, and inexpensive in manufacture.

With these and other objects in view, the invention consists in the construction, combination and arrangement of parts as will be hereinafter fully described, illustrated in the accompanying drawing, and pointed out in the claim hereunto appended.

In the drawing: Figure 1 is an enlarged fragmentary vertical longitudinal sectional view through a journal box, showing the waste guard in position therein, with the lid of the box closed. Fig. 2 is a plan view of the guard. Fig. 3 is a side elevation of the guard. Fig. 4 is a sectional view on the line 4-4 of Fig. 1.

Similar reference characters indicate corresponding parts throughout the several views in the drawing.

Referring to the drawings in detail, A designates a portion of a journal box, which is of the ordinary well-known construction, B the lid, C the pivot connecting it to the box A as usual to permit swinging movement of the lid to open or closed position, and D the spring which is mounted in the lid in the ordinary well-known manner to

act upon the same to hold it in closed position.

Passed within the journal box is the end portion of a journal 10 which engages with the bearings 11 as usual, the same mounted within the journal box. The dust guard comprises a curved plate 12 having rounded corners 13 at its lower edge which conform to the contour of the bottom portion of the journal box A, while the opposite upper edge of the plate 12 is formed with a flange 14 having struck therefrom medially of the same spaced ears 15 which are at right angles thereto, and which have integral therewith at one side of the same a web 16 which extends across the gap between the ears 15, and this web 16 serves as a bearing or abutment for one end of a substantially T-shaped leaf spring 17 which is formed with a bight 18 intermediate its ends adapted to be fulcrumed on a hub portion 19 integral with and arranged between the ears 15, while the opposite head end 20 of the spring 17 engages the inner face of the lid B on the journal box A, the said spring 17 being connected to the plate 12 by means of a rivet 21 so that the same will be united together.

The plate 12 is arranged within the journal box as shown in Fig. 1 so that the ears 15 will protrude into a notch or cavity 22 formed in the lid B, and this spring 17 will exert a tension upon the plate 12 to press it against opposed studs 23 formed interiorly of the journal box A at opposite sides thereof so that on the closing of the lid B the plate 12 will be automatically positioned to engage the shoulder 23 on the bottom of the journal box, as shown in Fig. 1 of the drawing, to sustain the waste containing the oil in proper position at the under side of the journal 10 within the journal box.

On the raising of the lid B of the journal box A the studs 23 will guide the plate 12 against the resistance of the spring 17 so as to free the lower edge of the plate from the shoulder 23 interiorly of the journal box, and thus permit access to be had to the waste for the supplying of the same with oil.

From the foregoing it is thought that the construction and manner of use of the device will be clearly understood, and therefore a more extended explanation has been omitted.

What is claimed is:—

The combination with a journal box having a lid, of a waste guard mounted upon

the lid, means within the journal box for guiding the waste guard during the opening and closing of the lid, tension means operative upon the waste guard to hold the same relative to the guiding means, and a hub formed on the waste guard and serving as a fulcrum for the tension means.

In testimony whereof I affix my signature in presence of two witnesses.

CHARLES W. RENNER.
